CLAIM

An ornamental design for a protective safety tensioning device, as shown and described.

DESCRIPTION

FIG. 1 is a perspective view of the protective safety tensioning device showing the design;
FIG. 2 is a front elevational thereof;
FIG. 3 is a rear elevational view thereof;
FIG. 4 is a bottom plan view thereof;
FIG. 5 is a top plan view thereof;
FIG. 6 is a left side view thereof; and,
FIG. 7 is a right side view thereof.

1 Claim, 5 Drawing Sheets
